NONPLUGGING COUPLING FOR ROTARY DRILLS

Application filed September 24, 1927. Serial No. 221,691.

This invention is an improvement in non-plugging bits or tools, and more particularly in a device of the class mentioned especially designed for deep well drilling.

5 In the usual construction of tools, a passage is provided extending longitudinally thereof, for conducting water to the bottom of the well, to convert into a fluent mixture, the cuttings of the drill, to prevent blocking 10 of the drill by said cuttings.

Water or other fluid is driven through the passage, as for instance by a pump, and regurgitation is prevented by a check valve arranged at a suitable point in the passage, 15 usually in the coupling, and it passes up around the drill, the operation of the drill providing a churning action, which hinders and prevents settling of the cuttings about the cutting end of the drill.

20 Because of the large content of cuttings there is great liability to blocking of the passage, particularly at the check valve, and especially if there is any change in direction of the fluid at this point.

25 In order to insure a maximum circulation, it is desirable that there be a minimum of friction in the passage of the fluid, that is that the passage be as nearly straight as possible.

30 One of the primary objects of the present invention is the provision of a construction of coupling, wherein the passage for the fluid offers a minimum of friction, and of waste space for the collection of sediment.

35 Another object is the provision of a valve which in itself offers but little resistance to the passage of the fluid, and which is reversible, in order to provide for double wear.

Another object is the provision of a construction of valve wherein the working parts are easily accessible for removal and repair.

With these and other objects in view the invention consists in the construction and novel combination of parts fully described 45 hereinafter, illustrated in the accompanying drawings, and pointed out in the claims appended hereto, it being understood that various changes in the form, proportion, size and minor details of construction within the scope 50 of the claims, may be resorted to without

departing from the spirit of the invention.

In the drawings forming a part hereof:

Fig. 1 is a longitudinal section of an embodiment of the invention.

Fig. 2 is a section on the line 2—2 of Fig. 1. 55

Figs. 3 and 4 are views similar to Fig. 1 of other embodiments of the invention.

In the embodiment of Figures 1 and 2, the improvement is shown in connection with a coupling, comprising a body 1, of substantially cylindrical shape, having at one end a tapering internally threaded socket or box 2, and at the other an externally threaded pin 3 shaped to fit the box 2. By means of the box and the pin, the coupling is adapted to connect two parts of the string of tools, the pin 60 engaging the box of one part, and the box receiving the pin of another part.

The coupling is provided at the pin end with an axial passage 4, which divides, in the 70 pin, into a pair of similar passages 5 extending longitudinally of the tool, and opening into the box. By means of these passages 4—5, a circulation of fluid, as for instance water, may be maintained through the drill 75 or other tool to the bottom of the well, it being understood that the drill or other tool is provided with passages registering with the passages 5, and forming continuations thereof. 80

In the present construction a valve is arranged at the connection between the passage 4 and the passages 5. This valve comprises a body 6 of substantially cylindrical formation, having a conical or tapering extension 85 7 at each end, the said ends being similar, and one of the ends is adapted to engage the open end 8, of a tubular valve seat 9, threaded into the passage 4. The other conical end of the valve is engaged by a spring to be described, 90 normally holding the valve to its seat.

That portion of the coupling body between the passages 5, and their connection with the passage 4, is recessed as shown at 10, to form a species of socket, for receiving one end of the spring 11, arranged in the socket, between the valve and the bottom of the socket. As shown the spring is helical, one end fitting about the tapered or conical end of the valve 6, thus assisting in centering the valve. In 100

order to prevent clogging of the socket 10 by sand or the like, and to enable a free escape of liquid therefrom, openings 12 are provided in the bottom of the socket, the said 5 openings leading to the passages 5.

In operation, the valve enables free flow of the fluid from the passage 4 to the passages 5, but acts as a check to prevent regurgitation thereof. It is accessible for any purpose, 10 merely by unthreading the seat 8, which is internally polygonal in cross section, for engagement by a suitable tool. Either end of the improved valve is designed to cooperate with the seat, and in case of wear, or for any 15 other reason, the valve may be turned, thus providing a fresh engaging surface.

The valve prevents blocking of the passage 4 through sand and the like passing upward through the passages 5 into the said passage. 20 Should this occur, circulation of the liquid could not be had, and it would then be necessary to pull the drill stem to wash out the formation packed into the stem above the bit. Without a valve, either when working or 25 when idle, the plugging of the passages 4 and 5 is liable to occur.

It will be obvious that the improved valve is arranged as shown in Fig. 1, only when the 30 pin of the coupling is to be upward. If the pin of the coupling is to be downward, the parts will be arranged as shown in Fig. 3. In this construction, the valve indicated at 13 and similar to the valve 6, cooperates with a seat 14 of tubular shape, threaded into an 35 opening in the body of the coupling 15 just below the box 16. The seat is internally polygonal in cross section, to facilitate removal thereof, thereby to enable access to the valve.

The valve is held to its seat by a spring 17, 40 similar to the spring 11, and similarly arranged. The spring is held in a socket 18 at the axis of the body of the coupling, and the socket has the vent openings, not shown, corresponding to the openings 12 of Fig. 1. The 45 operation in the present arrangement is precisely the same as that of Fig. 1, the valve acting to prevent upward flow of the liquid, and to prevent the entrance of sand and the like into the passages above the coupling.

50 In Fig. 4, a construction of coupling is shown, adapted for use with either end upward. In this arrangement the coupling 19 has the pin 20 at one end, and the box 21 at the other. A seat 22 has threaded engagement with the upper end of the axial opening in the pin, and a valve 24 cooperates with the seat, the valve being held to the seat by a spring 25, one end of which rests within the socket 26. These parts correspond with the 55 similar parts of Fig. 1, and the operation is the same when the pin is up.

At the lower end a seat 27 is threaded into an axial opening in the body just above the box 21. A valve 28 cooperates with the seat, 60 and a helical spring 29 normally presses the

valve to the seat. The construction at this end is like that shown in Fig. 3, and operates in the same manner. The internal openings of the seats 22 and 27 are polygonal in cross section to enable easy unthreading thereof.

With the Fig. 4 construction, when the pin is up, the seat 27, the valve 28, and the spring 29 are removed. When the coupling is to be used with the box up, these parts are replaced and the seat 22, the valve 24, and the spring 25 are removed. In either case the flow of the fluid must be downward, and any regurgitation thereof is prevented. The improved coupling may be used in any part of the string of stools, but a preferable location is near the bottom of the string, as for instance between the bit and the drill stem. In this location the maximum amount of passage through the string is protected against the entrance of foreign matter, whether from "heaving" when idle, or from cuttings when at work.

What is claimed as new is:—

1. A coupling having at one end a tapering box and at the other a tapering pin shaped to fit a similar box, said coupling having passages extending from near one end to near the other and opening at the said other end by a single passage, a seat having threaded engagement with said other end, a valve cooperating with the inner end of the seat and of less external diameter than the seat, thereby to enable removal of the valve when the seat is detached, and a spring pressing the valve to the seat, said valve substantially cylindrical and having similar conical ends, one to engage the seat and the other to be engaged by the spring to center the valve.

2. A tool of the class described, provided at one end with a pin and at the other with a box, and having a longitudinally extended passage, the pin end being reamed to provide an opening for a valve seat and a socket of reduced diameter beyond the seat, said passage opening into the reamed part between the opening and the socket, a seat detachably engaged with the tool in the opening, a valve cooperating with the seat, and a spring in the socket normally holding the valve to its seat.

Signed at the American Consulate in Tampico, Mexico, and State of Tamaulipas, this 9th day of September, A. D. 1927.

BENJAMIN E. PARRISH.
FRANK BAQUET.
